UNITED STATES PATENT OFFICE.

CHARLES MARKHAM CONDER AND GODFREY TWYNAM VIVIAN, OF CAMBORNE,
ENGLAND.

CRUSHING-MILL OF THE ROLLER AND RING TYPE.

1,374,823.

Specification of Letters Patent. Patented Apr. 12, 1921.

Application filed December 10, 1920. Serial No. 429,756.

To all whom it may concern:

Be it known that we, CHARLES MARKHAM CONDER and GODFREY TWYNAM VIVIAN, both subjects of the King of Great Britain, and both residing at Camborne, in the county of Cornwall, England, have invented certain new and useful Improvements in Crushing-Mills of the Roller and Ring Type, of which the following is a specification.

10 This invention relates to that class of crushing, grinding or pulverizing mills which comprise a rotating annular anvil ring against the inner surface of which crushing or hammer rollers are pressed, the 15 crushing operation being effected between the anvil ring and the rollers. This invention comprises certain improvements which render this class of machines more convenient in use and more effective in 20 operation.

According to the present invention the annular anvil ring is preferably mounted on a shaft not having a fixed axis, but which is capable of accommodating itself to the 25 center of pressure between the rollers, and thus equalizes the amount of material between the rollers and the ring. Certain other improvements are introduced which will be hereinafter more fully set forth.

30 In the accompanying drawings is shown an example of construction according to the present invention.

Figure 1 shows an end elevation of the machine, with the driving pulley removed and swivel bearing frame broken away so as to show the slide block and spring arrangements.

Fig. 2 is a side elevation of the machine.

Fig. 3 is a section through the springs and 40 slide blocks showing adjustments.

Fig. 4 is a plan, with the casing partly broken away so as to show one of the rollers and a portion of the ring.

Referring to the drawings, 1 denotes the 45 base of the machine on which are mounted the half head casting 2, the supporting frame 3 for the slide blocks 4, and the frame 5 carrying the swivel bearings 6. The annular anvil ring 7 is carried on a spider frame 8 mounted so as to turn on a shaft 9 provided with journals 10 suitable for sliding on bearing surfaces in the half head casting 2. Shafts 12 are mounted at one end in swivel bearings 6 carried by the 50 frame 5, and near their other end in slide

bearings 4 arranged close up to the head casting 2. These slide bearings are supported on the slide frame 3 and are pressed outwardly toward the inside of the annular ring by means of springs 13. On the ends 60 of the shafts 12, which are preferably tapered and project inside the anvil ring 7, are mounted rollers 11 adapted to crush or grind the material between them and the inside of the anvil ring 7. As the shafts 12 65 and consequently also the rollers 11 are capable of lateral sliding movement the rollers 11 are enabled to accommodate themselves to the center of pressure between them and the ring 7 coöperating therewith. In this manner the feed of material between the ring and the rollers is equalized as the rollers would move to the center of pressure and equalize the material if more material should be disposed at one point between one 70 of the rollers and the ring. In operation should any hard or uncrushable substance be fed between any roller 11 and the ring 7, the spring or springs 13 yield, and prevent any fracture of the machine, while the 75 crushing pressure which is consequently increased due to the springs compressing is equal and opposite being exerted on the two rollers 11 diametrically opposed inside the annular anvil ring 7.

85 For crushing materials of varying hardness screw collars 14 are adapted to be screwed on screwed pins or studs 15 provided on the slide blocks 4 so that the tension of the springs arranged between the 90 blocks 4 can be varied. Packing pieces or shim plates 16 are preferably inserted between the screw collars 14 and the slide blocks 4 so as to take the pressure, during working, off the threaded pins 15. The 95 opposite ends of the springs 13 are arranged to fit around bosses 30 provided on the blocks 4. The axes of the roller shafts 12 are at an angle to the horizontal to facilitate the feed, while the tendency for the weight 100 to keep the roll shafts 12 in the lower position is counteracted by a suitable spring 28 arranged between a lug 31, cast on the frame 3 and the lower slide block 4. The lower end of the spring 28 is adapted to act against 105 the head of a screw pin 27 which screws into a tapped hole in the lug 31 on the frame 3 and when the correct position for the roller shafts 12 has been obtained, by adjusting 110 the position of the screw pin 27, packing

pieces or shim plates 29 are inserted between the head of the pin 27 and the lug 31.

One of the roller shafts 12 is extended beyond the swivel bearing 6 and has a belt pulley 16 keyed thereto for driving the machine. On the shafts 12 are mounted suitable sprocket wheels 17 connected together by an endless chain 32. It will be understood that the object of driving both rollers positively is that the wear on the rollers is equalized and any slip with the resulting wear is avoided. The half head casting 2 hereinbefore described has ears or lugs 18 cast thereon which are adapted to receive hinge pins 19, passing through similar ears or lugs 33 on the top covers 20, 21. The cover 21 carries the feed chute 22 and hopper 23. A cut-off slide 24 is arranged to operate in a slot machined in the base of the hopper 23 and is drawn in or out by means of a lever 25 attached to a lug 34 by means of a pivot pin 26. By forming the

top cover in two parts 20, 21 as set forth, it is possible to swing back the part 20 and inspect the rollers 11 and the ring 7 in their 25 respective working positions.

Having thus described our invention what we claim as new and desire to secure by Letters Patent is:—

A machine for crushing materials including a frame, an anvil supported by the frame, a pair of shafts, movable bearing blocks supported on the frame in which the shafts operate, crushing rollers mounted on the shafts and adapted to coöperate with the 35 anvil, resilient means disposed between the bearing blocks for normally urging them away from each other, and resilient means normally exerting a pressure on one of the bearing blocks to urge the same toward the 40 opposite bearing block.

CHARLES MARKHAM CONDER.
GODFREY TWYNAM VIVIAN.
